UNITED STATES PATENT OFFICE.

EDWARD SIMON, OF MONTREAL, QUEBEC, CANADA.

DESIGN FOR A CIGAR LIGHTER.

Application filed June 22, 1925. Serial No. 13,841. Term of patent 7 years.

To all whom it may concern:

Be it known that I, EDWARD SIMON, a subject of the King of Great Britain, of 300 Atlantic Avenue, in the city of Montreal, Province of Quebec and Dominion of Canada, have invented a new, original, and ornamental Design for a Cigar Lighter, of which the following is a specification, reference being had to the accompanying drawings, forming part thereof:

The figure is a perspective view of a cigar lighter showing my new design.

I claim:

The ornamental design for a cigar lighter, as shown.

In witness whereof, I have hereunto set my hand.

EDWARD SIMON.
